United States Patent Office

Des. 184,963
Patented Apr. 21, 1959

184,963

LIPSTICK DISPLAY STAND

Jerry F. Roesch, Indianapolis, Ind.

Application July 11, 1958, Serial No. 51,777

Term of patent 14 years

(Cl. D80—9)

Fig. 1 is a perspective view of my new lipstick display stand.

Fig. 2 is a top plan view thereof.

Fig. 3 is a side elevation view thereof.

I claim:

The ornamental design for a lipstick display stand, as shown.
